GAS-OPERATED, SPRING-ROTATED, AUTOMATIC CHOKE DEVICE FOR SHOTGUNS

Haskell E. Metz, Marion, Ohio

Application June 16, 1955, Serial No. 515,899

1 Claim. (Cl. 42—79)

This invention relates to choking devices for shotguns, and has particular reference to adjustable choke devices which may be automatically adjusted in response to firing of the gun.

A general object of the invention is to provide a new and improved adjustable gun choke wherein a torsion-type spring is utilized for supplying the torque energy necessary for automatically rotating a barrel-carried sleeve employed in constricting a barrel muzzle.

Another object is to provide such a rotatable sleeve of a gun choke with a resiliently movable latching element having a free end engaged normally with an adjoining stationary part of the gun barrel, whereby to preclude accidental choke-producing rotation of the sleeve.

Still another object is to provide a gun barrel with a restricted transverse port through which gases under pressure, developed by the firing of the gun, are caused to pass into pressure contact with a pressure-yieldable latching element, whereby to actuate the latter in a manner removing the same from latching engagement with the barrel, thereby enabling the released sleeve to rotate under torque effort supplied thereto by an associated torsion spring in producing a choked or restricted gun barrel.

A further object is to provide an automatic choke for shotguns of the single barrel multiple shot type, wherein the choke is shifted automatically from one position to another, changing from an open or partly modified barrel to full choke immediately following an initial shot.

A still further object is to provide an automatic choke device for guns which is characterized by its positive and reliable operation and simplicity of construction and operation.

Again, another object is to so construct such an automatic choke as to enable the same, when desired, to be manually operated as a non-automatic but variable choke means.

These and other objects and advantages present in the construction will be more fully understood from a consideration of the following specification and annexed claim.

In the accompanying drawing:

Fig. 1 is a vertical longitudinal sectional view taken through the outer end of a shotgun barrel and disclosing the improved choke device of the present invention in its operative position thereon prior to the firing of a first shot;

Fig. 2 is a top plan view of the device in the position of Fig. 1;

Fig. 3 is a transverse sectional vertical view taken through the device on the line 3—3 of Fig. 1;

Fig. 4 is a similar view on the line 4—4 of Fig. 1;

Fig. 5 is a view partly in horizontal cross section and partly top plan disclosing the torsion spring-actuated sleeve of the choke device in its position producing full barrel choke following the firing of the first shot;

Fig. 6 is an end elevational view of the choke device and constrictable gun barrel extension, as indicated by the line 6—6 of Fig. 5;

Fig. 7 is a transverse sectional view on the line 7—7 of Fig. 1.

In the specific form of my improved choke device as it appears in the embodiment thereof illustrated in the above figures of the drawings, the outer or discharge end of a shotgun barrel is indicated at 10. The barrel includes the usual cylindrical bore 11 having a fixed or constant diameter, the extreme outer end portion of the barrel being externally threaded, as at 12. Engaged with these threads are those provided on the wall of an internally threaded counterbore 13 of a tubular barrel extension 14 of the improved choke device forming the present invention. The extension is formed with a bore 15 constituting normally a correspondingly sized continuation of the barrel bore 11. The counterbore 13 ends inwardly of the extension in an annular shoulder 16, which is maintained in any suitable manner during use of the choke device in firm seating engagement with the outer circular end of the barrel 10.

The outer or muzzle end of the extension is provided with a plurality of circumferentially spaced longitudinally extending slits or slots 17. These slits or slots extend transversely through the tubular wall of the extension, and are disposed longitudinally between the extreme outer end of the barrel attachment and positions midway of the length thereof. The slits or slots form between them resiliently yieldable fingers 18 which, when normally positioned, cause the bore 15 to possess throughout its length substantially the same diameter as the barrel bore 11, and when forced together to so constrict the muzzle end of the attachment as to produce a choke pattern on the part of shot fired therethrough.

The extreme outer ends of the fingers 18 of the extension 14 are outwardly beveled as at 19 for coaction with inwardly disposed beveled surfaces 20 of the outer section 21 of a choke sleeve assembly 22. The section 21 is internally threaded toward its inner end, as at 23 for engagement with external complementary threads formed intermediate of the extension 14. The sleeve assembly includes an inner section 25 which is counterbored at 26 to receive the correspondingly formed inner end of the outer section 21. A screw 24, or other equivalent means, may be used to hold the sections 21 and 25 in rigid assembled relationship. In fact, the sections 21 and 25 may, if desired, be formed as a single, integral part, but, for reasons of facility in adjustment, as will later appear, it is advantageous to employ the two-part formation, as here disclosed.

Fixed on the gun barrel 10 at a position spaced inwardly from the sleeve assembly is a split, spring-anchoring, adjustable collar 26. This collar is composed of two semicircular parts which are adapted to be clamped about the barrel to retain the collar in an adjustably fixed position thereon, bolts 27, or their equivalents, being employed ordinarily in effecting such clamping. One of these collar parts is formed to include adjacent to its periphery a longitudinal opening in which is received the longitudinally directed terminal 27a of a torsion spring 27b, here shown as being of the coiled wire type. This spring is disposed coaxially with the barrel between the inner end of the sleeve section 25 and the collar 26. The opposite terminal 28 of the spring is positioned in a longitudinal opening formed therefor in the inner sleeve section 25, as shown in Fig. 1.

Normally, the spring 27b is sufficiently tensioned by the rotatable adjustment of the collar 26 and relative rotation of the sleeve section 25, so that the torque effort exerted thereby, when released, will rotate the sleeve on the extension threads 24 in a manner advancing the sleeve assembly sufficiently in a longitudinal direction to engage the beveled surfaces 19 or 20 with one another and to resiliently contract the fingers 18 of the extension

muzzle, thus restricting the diameter of the bore 15. To retain the spring 27 under such tension while the surfaces 19 and 20 are relatively disposed to allow the fingers 18 to expand to open bore positions, as shown in Fig. 1, use is made of a latch means.

Such means in the construction illustrated, comprises a longitudinally extending spring bar 28^a. The outer end of this bar is fastened as at 29 to the inner section 25 of the sleeve assembly, while the inner end of said bar is slotted at 30 to receive a catch stud 31 projecting outwardly and radially from a second or inner split collar 32 stationarily mounted on the barrel 10 adjacent the outer collar 26. The extreme inner end of the bar 28 is formed with an inturned lip 33 which is received in an annular groove 34 formed in the peripheral surface of the collar 32. This recess is of sufficient width to receive the lip 33 in any longitudinally adjusted position of the sleeve sections. A restricted radial port or passage 34a is formed in the gun barrel 10 and the collar 32 in longitudinal alignment with the stud 31 and at a position in transverse registry with the outer resilient and free end portion of the bar 28^a when the latter is engaged with the stud 31.

In the use of my improved automatic choke attachment, the parts are positioned on the outer end of the gun barrel 10, as shown in Fig. 1. When so positioned the sleeve assembly will have been rotated in an anti-clockwise direction, when looking toward the muzzle end of the gun barrel, and the collar 26 rotated in a clockwise direction and clamped therein, as in Fig. 6, in order to place the spring 27 under tension in developing torque forces capable of rotating the sleeve assembly in a clockwise direction. To hold the spring under such tension, and to maintain the beveled surfaces 19 and 20 in open bore relation, the resilient latch bar has the slot 30 thereof disposed to receive the outwardly projecting stud 31 of the stationary collar 32.

With the parts of the attachment thus positioned, and as illustrated in Fig. 1, the firing of a first shot, because of unchoked bore diameter, will produce a normal relatively wide pattern of the scattering shot. As a result of gas pressures developed in the gun barrel from the initially fired shot, a part of such pressure will pass into and through the port or passage 34a, this action taking place with sufficient force to flex the inner end of the latch bar 28^a upwardly and releasing the same from engagement with the stud 31. Such release of the latch bar enables the tensioned coil spring 27 to respond at once and supply torque to rotate the sleeve assembly on the threads 24 of the barrel extension in a direction causing the sleeve assembly to move inwardly and longitudinally of the barrel to the position shown in Fig. 5. In this position, the beveled surface 20 moves inwardly over the cooperatively beveled surfaces 19 to flex the fingers 18 radially inwardly to muzzle-constricting positions, so that when a second shot is fired, the shot pattern produced thereby will be more concentrated than that of the first shot, whereby to compensate for the greater distance between the gun and receding targets.

While I am aware that the prior art proposes the employment of automatically operating choke devices for shotguns in which muzzle constriction is produced by recoil and/or gas pressures developed as a result of the firing of an initial shot, yet, none of these prior proposals has found commercial acceptance, since only conventional manually operated types of chokes are now in practical use. This condition is believed to be attributable to the unreliability of the mechanisms used in the prior automatic types of devices and their general ineffectiveness

for intended purposes. Thus, it has been proposed to rotate the choke sleeves by the impingement of shot-developed pressure gases on angular blade surfaces formed on the outer ends of the sleeves. Again, it has been proposed to slide the sleeves longitudinally on the barrel extensions by the use of trigger-released springs. Greater reliability and more positive operation, however, is obtained with the use of the torsion spring of the present invention over these prior proposals, particularly through the high torque effect which such a torsion spring produces on an associated thread-carried sleeve, whereby to cause said sleeve to move positively and effectively in contracting the resilient choke fingers of the barrel extension. Moreover, the simplicity and low cost of the present construction is another important factor in its favor.

The outer and inner sections 21 and 25, respectively, of the sleeve assembly provide for the relative adjustment thereof in a manner maintaining the effective bore diameter of the gun barrel extension best adapted to the liking of different gun users, and such adjustments may be maintained by the employment of the screw 24. Also, the barrel extension may be turned manually, instead of automatically, if desired, by loosening the adjustable collar 26 and thereby removing spring tension.

While I have set forth and described in detail a single preferred embodiment of the automatic gun choke forming the present invention, it will be understood that this embodiment is but an illustrative or exemplary one, and, therefore, the construction thereof is subject to certain variation or modification falling within the scope of the appended claim.

I claim:

35 In combination with a shotgun having a barrel; a radially, resiliently constrictible muzzle extension attached to the muzzle end of said barrel and forming a longitudinal continuation thereof and operable to vary the pattern of shot fired therethrough; a sleeve member threadedly carried on said muzzle extension and operable upon 40 rotation in one direction to constrict said extension; a torsion spring positioned around the barrel of the shotgun adjacent said sleeve member and having an end thereof connected directly with said sleeve member; means stationarily securing an opposite end of said spring to the 45 barrel of said shotgun, said spring being arranged to urge said sleeve member to rotate in said one direction to constrict said muzzle extension; a resiliently flexible latch arm carried for rotation with said sleeve member and extending longitudinally inwardly of the barrel of said shotgun over and beyond said spring; catch means stationarily mounted on the barrel of the shotgun rearwardly of said spring and engageable with said latch arm to hold said sleeve member against muzzle-constricting 50 rotation and said spring under tension; and means, comprising a gas passage extending radially through the barrel of said shotgun and in longitudinal alignment with said catch means, operable in response to the firing of the shotgun to disengage said latch arm from said catch means and thereby cause said sleeve member to rotate in said 55 one direction under influence of said torsion spring.
